UNITED STATES PATENT OFFICE

171,441

TAG DISPENSING DEVICE

Morris Cornick, Chicago, Ill.

Application February 9, 1953, Serial No. 23,488

Term of patent 14 years

(Cl. D80—9)

To all whom it may concern:

Be it known that I, Morris Cornick, a citizen of the United States, residing at Chicago, State of Illinois, have invented a new, original and ornamental Design for a Tag Dispensing Device, of which the following is a specification, reference being had to the accompanying drawing, forming a part thereof.

Fig. 1 is a perspective view of a tag dispensing device embodying my new design.

Fig. 2 is a top plan view of the same.

Fig. 3 is a front elevational view of the same.

Fig. 4 is a sectional view taken generally along the line 4—4 of Fig. 2 and in the direction indicated by the arrows.

I claim:

The ornamental design for a tag dispensing device, as shown.

MORRIS CORNICK.
